UNITED STATES PATENT OFFICE.

GARFIELD FORCE, OF BROOKLYN, NEW YORK.

DESIGN FOR A BADGE.

51,411.

Specification for Design.

Patented Oct. 23, 1917.

Application filed September 7, 1917. Serial No. 190,278. Term of patent 3½ years.

To all whom it may concern:

Be it known that I, GARFIELD FORCE, a citizen of the United States, residing at Brooklyn, in the county of Kings and State of New York, have invented a new, original, and ornamental Design for Badges, of which the following is a specification, reference being had to the accompanying drawing, forming a part thereof.

The figure is a plan view of a badge, showing my new design.

I claim:

The ornamental design for a badge, as shown.

GARFIELD FORCE.
